DOOR CLOSING DEVICE

Charles F. Fay, Earlimart, Calif.

Application May 15, 1935, Serial No. 21,512

3 Claims. (Cl. 16—76)

This invention relates generally to a door closing device and is directed particularly and specifically to a spring actuated door closing mechanism.

5 Most door closing devices which are now sold on the market require that screws be employed to hold the mechanism in place and in many instances these devices are relatively large and cumbersome as well as expensive, and frequently 10 the holding screws tear loose. If it is ever desired to remove such a device from the door, unsightly screw holes will remain.

The principal object of my invention is to provide a door closing device which requires no 15 screws or bolts to hold the same in place and which is supported by a pin readily substituted in place of one of the removable hinge pins of the door.

An additional object of my invention is to provide a door closing device which will close 20 the door and cause the same to latch without slamming the door. My improved door closing device is also very neat in appearance and may be easily and quickly installed on a door.

25 A further object of the invention is to produce a simple and inexpensive device and yet one which will be exceedingly effective for the purpose for which it is designed.

These objects I accomplish by means of such 30 structure and relative arrangement of parts as will fully appear by a perusal of the following specification and claims.

In the drawing similar characters of reference indicate corresponding parts in the several 35 views:

Figure 1 is an elevation illustrating my door closing device as installed on a door.

Figure 2 is a top view of the device as installed 40 on a door illustrating in dotted lines the relative position of the parts of the device when the door is open.

Figure 3 is a view of the hinge pin and spring support detached.

Referring now more particularly to the characters of reference on the drawing, the numeral 45 1 denotes a door hinged at 2 to a casing 3. Replacing the usual hinge pin is a combination hinge and spring supporting pin comprising a shank 4, a right angle offset 5, and an upstanding finger 6 parallel to the shank.

50 Non-rotatably mounted on the finger 6 is a tough but resilient cylindrical rubber core 7. Tightly wound about this rubber core 7 is a helical torsion spring 8 of relatively heavy spring steel wire. The spring wire forming this helical

spring 8 projects from each end of the spring in opposite directions to form horizontal straight arms 9 and 10 respectively.

Formed on the outer end of the arm 9 at right angles thereto is a downwardly extending casing 5 engaging finger 11. The lower end of this finger is formed with a horizontal extension 12 projecting in the direction of the hinge 2.

The outer end of the arm 10 is also provided with a finger 13 which extends upwardly from the arm 10 and at right angles thereto.

The finger 11 and horizontal extension 12 as well as the finger 13 are encased in rubber sleeves 14 and 15 respectively.

To install my improved door closing device, 15 one of the hinge pins is removed and the shank 4 of combination hinge and supporting pin inserted in its place with the finger 6 positioned outwardly of the hinge as illustrated in Figure 2. With the pin thus in position the fingers and rubber sleeves of the arms 9 and 10 will firmly engage 20 against the surface of the casing and door respectively due to the fact that the spring 8 is under some tension when the arms are substantially 180° apart and is wound to exert a torque 25 in a door closing direction. Also, on account of the offset finger, the spring itself never rubs against the door or casing.

In operation, when the door 1 is opened the arm 10 is moved forward in a direction to increase 30 the torque of the spring 8 and the shank 4 tends to rotate within the hinge, thus moving the entire assembly to the position indicated in dotted lines in Figure 2. It is therefore impossible for the door to contact the spring at 35 any time, even when fully open.

When the door is open and the spring 8 exerting greater torque, the diameter of the spring decreases. The use of the rubber core allows this decrease in size of the spring to take place as 40 well as providing a permanent close fitting mounting for the spring. Squeaks or rattling noises in operation are therefore avoided.

The rubber sleeves 14 and 15 of course prevent any scratching or injury to the contacted 45 surface of the casing and door while the horizontal extension 12 holds the entire arm and spring structure from tilting forward under the influence of the spring.

In manufacture, the spring 8 may be made to 50 exert different pressures according to the particular type of door upon which the device is to be used.

From the foregoing description it will be readily seen that I have produced such a device as 55

substantially fulfills the objects of the invention as set forth herein.

While this specification sets forth in detail the present and preferred construction of the device, 5 still in practice such deviations from such detail may be resorted to as do not form a departure from the spirit of the invention, as defined by the appended claims.

Having thus described my invention, what I 10 claim as new and useful and desire to secure by Letters Patent is:

1. A closing device for a hinged door comprising a pin adapted to replace one of the hinge pins and to extend beyond the hinge, a resilient core mounted on the extended portion of the pin, a torsion spring wound about the core, and opposed arms projecting from opposite ends of the spring and engaging the door and its casing respectively; said spring being coiled to 20 exert a door closing torque.

2. A closing device for a hinged door comprising a pin adapted to replace one of the hinge pins and to extend beyond the hinge, said extended portion being forwardly offset, a torsion spring mounted on the extended portion of the pin, opposed arms projecting from opposite ends of the spring and engaging the door and its casing respectively; said spring being coiled to exert a door closing torque. 5

3. A closing device for a hinged door comprising a pin adapted to replace one of the hinge pins and to extend beyond and in forwardly offset relation to the hinge, a resilient core mounted on the extended portion of the pin, a torsion spring wound about the core, and opposed arms 15 projecting from opposite ends of the spring and engaging the door and its casing respectively; said spring being coiled to exert a door closing torque.
